ROCK DRILL

Ezra B. Mead, Ottumwa, Iowa, assignor to
Hardsocg Wonder Drill Co., Ottumwa, Iowa, a
corporation of Iowa

Application July 26, 1939, Serial No. 286,675

6 Claims. (Cl. 121—10)

The present invention relates to rock drills of the type operated by compressed air and it primarily has for its object to provide such a drill with improved valves so arranged and combined that, without changing the position of the main control valve, the hole being drilled may be blown by the simple operation of a push-button valve device directly connected with the source of air supply to the drill, and whereby the main valve may be used to direct the air for blowing the hole to the blow tube.

Again, it is an object to provide a drill of the character stated in which water may be delivered to the blow tube, while the air is also passing thereto, either while the drill is stopped or while it is running slowly, as may be desired.

Further, it is an object to provide a blowing device which is simple and effective in operation, inexpensive to construct and maintain, and in which the use of valve springs may be omitted.

Other objects will in part be obvious and in part be pointed out hereinafter.

To the attainment of the above objects and ends the invention still further resides in those novel features of construction, combination and arrangement of parts, all of which will be first fully described in the following detailed description and then be particularly pointed out in the appended claims, reference being had to the accompanying drawings, in which:

Fig. 1 is a vertical section, on a small scale, on the line 1—1 of Fig. 2, showing a rock drill embodying the invention.

Fig. 2 is an enlarged top plan view of the same, parts being broken away.

Fig. 3 is a section of the top or back head and the parts (other than the blow tube and ratchet bar) carried thereby.

Fig. 4 is a diagrammatic view of the parts of the back head with the invention applied.

In the drawings, in which like numbers of reference indicate like parts in all the figures, 1 designates the cylinder, 2 the piston, 3 the exhaust grooves, 4 the exhaust ports, 5 the piston's hammer part, 6 the grooves in the hammer part, 7 the friction ring which closes the upper end of the working chamber and 8 the cylinder collar which constitutes the closure for the lower end of the working chamber.

The cylinder has live air inlet ports 9 (bottom end) and 13 (top end), a fluid delivery duct 10 whose entrance ports 11 are at the shifting valve device 12; another set of ports 13 effects communication between the shifting valve and the upper end of the working chamber.

The shifting valve device may be of any usual kind, but I prefer to use the flap valve device of the kind shown in Fig. 1 and constituting the subject matter of another application, filed July 19, 1939, Ser. No. 285,449.

The cylinder 1 also has a live air duct 14 which conveys the live air from a duct 41 in the top or back head 20 to the valve device 12.

The front end 15 of the cylinder carries the rotatable sleeve 17 whose feathers or keys 18 register with the grooves 6. The sleeve 17 has its lower end threaded internally and carries the chuck or holder 16 for the drill steel 19 (see Fig. 1).

The back head 20 has the bored part 21 to receive the handle bolts 59 (of ordinary construction). It is also bored and tapped at 22 to provide a chamber 55 and to receive a chambered plug 23, which not only closes the chamber 55 at the top but also aids the hollow-tube carrier 54 in supporting the blow tube 53. The head 20 is also provided with a bore 24 constituting a valve chamber.

A duct 25 leads from this chamber 24 to the chamber 55 directly.

The push-button valve comprises a body having upper and lower piston portions 26, 28 respectively, separated by a neck 27. The piston portion 28 has an annular groove 32 which, when the valve is closed, communicates with duct 35, later again referred to.

The closed position of this valve is determined by engagement of the flange 29 with the shoulder formed at the juncture of the smaller with the larger parts of the chamber 24.

The push-button valve may have an extension with a pocket to receive a spring 31 which may be used, if desired, to move the valve to the closed position or to assist in such movement. However, by properly proportioning the valve structure, spring 31 becomes unnecessary, as the air admitted into the enlarged end of the chamber 24, through port 34, will suffice to move the valve to closed position.

A button or head 33 is secured to the valve and provides a shoulder to engage the back head 20 on the down or in-stroke of the valve and limit it to a fully open position for effecting communication between ducts 35 and 25.

The back head also has an air space 36 into which, at 44, is screwed the gland-nut 45 which carries the air inlet pipe 46. The space 36 is in constant communication with the source of compressed air supply via pipe 46 and also constantly communicates with duct 35.

A main valve 38 fits into a valve seat bore 37 and has its free end in chamber 36. It has a stem 57 which is fitted with a handle 58 (Figs. 4 and 2). It also has a pocket or chamber 40 that constantly communicates with the air space 36. Ports 39 are provided for conducting the motive fluid from chamber 36 to duct 14 via 41, while a port 42 is designed, in one position of the valve, for registering with the duct 43. The main valve 38 also has a small port 56 for leading air to port 41 for slow running of the drill.

The back head 20 may, at a suitable place, have a duct 47 for delivering water to chamber 55 with which duct a water hose 48 and shut-off valve 49 are connected.

50 designates a ratchet ring and 52 indicates the ratchet bar which is rifled to fit the rifle-nut 51 for the usual purposes.

The blow tube 53 is secured in the carrier 54 and which is held in place by plug 23.

The parts 1, 15 of the drill case and the head 20 may be bolted together by bolts 60, as shown in Fig. 2.

From the drawings it will be seen that the blow tube 53 extends through the center of the ratchet bar 52 and through piston 2—5. It may or may not be extended into the hole 61 of the drill steel as desired. In a dry drill it need not extend into the drill steel, but in a drill using water to allay the dust it should extend into the steel as shown in Fig. 1.

Operation

Assume the parts to be positioned as in Figs. 1 and 4. Air will pass from chamber 36 through main valve 38, ports 39, 63, ducts 41-14 to distributing valve 12 for effecting a normal operation of the piston 2, etc., at such speed as desired accordingly as ports 39 are open, more or less. Air under pressure will also occupy duct 35 and port 34 and the lower end of chamber 24, thus holding push-button valve closed.

To blow the hole, the valve 33, 26, 27, 28, 29 is pushed in until piston 28 clears duct 35, which allows full pressure air to flow via duct 25 to chamber 55, and from thence through 53 and the drill steel to the hole. The push-button valve is operable regardless of the position of valve 33.

An independent method of blowing is also provided for. The duct 41 has its ends 63 separated, leaving a blind center portion 62. In alignment with this portion 62 the port 42 of the valve 38 is located. The ports 39, 42 and 56 are so arranged that when lever 58 is in one position all ports will be closed; when the lever is in a second position ports 39-39 will be open and ports 56 and 42 will be closed; when in a third position ports 56 and 42 are open.

When the operator has reached the limit of one length of steel 19, he moves handle lever 58 to the position where port 42 registers with duct 43 to blow the hole, and then moves lever 58 to a position where all ports of the valve 38 are closed.

When water is used to lay the dust, it is admitted by the hose 48 and regulating valve 49, not a part of the drill proper. The regulating valve 49 is of such type as to permit the water to seep continually into space 55, from which it is blown through the blow tube. Water used in this connection is invariably at a lesser pressure than the air. In case of excessive opening of its needle valve 49 water might flood the ducts 25, 43, but due to the higher air pressure it could not go beyond the valves 26 etc., and 38. The idea is so to adjust the pressure and amount of water fed as to prevent this flooding.

Since the drilling engine is of conventional construction, save as above indicated, further description of its operation is thought to be unnecessary.

From the foregoing description, taken in connection with the accompanying drawings, it is thought that the complete construction, operation and advantages of the invention will be clear to those skilled in the art to which it relates.

What I claim is:

ber and the entrance of said blow tube, a push-button valve for controlling passage through said duct, said duct being independent of said throttle valve, another duct leading from said throttle valve to the entrant end of said blow tube independent of said push-button valve, and a third duct leading from said throttle valve toward the working chamber of the drill, said third duct having two entrance ports and said throttle valve having two separated ports for communicating with said two entrance ports, and having a third port located in a plane between said two separated ports for communication with said second duct, said throttle valve also having a minimum feed port for communication with said third duct when said two separated ports are out of communication with said two entrance ports and said third port is in communication with said second duct.

5. In a rock drill, having a back head unit and a blow tube carried thereby, and having a working chamber, a main throttle valve carried in said head, said head having an air receiving chamber in communication with said throttle valve, means to deliver compressed air into said air receiving chamber, a duct between said air receiving chamber and the entrance of said blow tube, a push-button valve for controlling passage through said duct, said duct being independent of said throttle valve, another duct leading from said throttle valve to the entrant end of said blow tube independent of said push-button valve, a third duct leading from said throttle valve toward the working chamber of the drill, said throttle valve having ports for communication with said second and third ducts separately, said first duct having offset ports communicating with the valve chamber of said push-button valve at two levels, said push-button valve including a

10. Having two separated ports for communicating with said two entrance ports, and having a third port located in a plane between said two separated ports for communication with said second duct, said throttle valve also having a minimum feed port for communication with said third duct when said two separated ports are out of communication with said two entrance ports and said third port is in communication with said second duct.

15. In a rock drill, having a back head unit and a blow tube carried thereby, and having a working chamber, a main throttle valve carried in said head, said head having an air receiving chamber in communication with said throttle valve, means to deliver compressed air into said air receiving chamber, a duct between said air receiving chamber and the entrance of said blow tube, a push-button valve for controlling passage through said duct, said duct being independent of said throttle valve, another duct leading from said throttle valve to the entrant end of said blow tube independent of said push-button valve, a third duct leading from said throttle valve toward the working chamber of the drill, said throttle valve having ports for communication with said second and third ducts separately, said first duct having offset ports communicating with the valve chamber of said push-button valve at two levels, said push-button valve including a

20. Having two separated ports for communicating with said two entrance ports, and having a third port located in a plane between said two separated ports for communication with said second duct, said throttle valve also having a minimum feed port for communication with said third duct when said two separated ports are out of communication with said two entrance ports and said third port is in communication with said second duct.

25. In a rock drill, having a back head unit and a blow tube carried thereby, and having a working chamber, a main throttle valve carried in said head, said head having an air receiving chamber in communication with said throttle valve, means to deliver compressed air into said air receiving chamber, a duct between said air receiving chamber and the entrance of said blow tube, a push-button valve for controlling passage through said duct, said duct being independent of said throttle valve, another duct leading from said throttle valve to the entrant end of said blow tube independent of said push-button valve, a third duct leading from said throttle valve toward the working chamber of the drill, said throttle valve having ports for communication with said second and third ducts separately, said first duct having offset ports communicating with the valve chamber of said push-button valve at two levels, said push-button valve including a

30. Having two separated ports for communicating with said two entrance ports, and having a third port located in a plane between said two separated ports for communication with said second duct, said throttle valve also having a minimum feed port for communication with said third duct when said two separated ports are out of communication with said two entrance ports and said third port is in communication with said second duct.

35. In a rock drill, having a back head unit and a blow tube carried thereby, and having a working chamber, a main throttle valve carried in said head, said head having an air receiving chamber in communication with said throttle valve, means to deliver compressed air into said air receiving chamber, a duct between said air receiving chamber and the entrance of said blow tube, a push-button valve for controlling passage through said duct, said duct being independent of said throttle valve, another duct leading from said throttle valve to the entrant end of said blow tube independent of said push-button valve, a third duct leading from said throttle valve toward the working chamber of the drill, said throttle valve having ports for communication with said second and third ducts separately, said first duct having offset ports communicating with the valve chamber of said push-button valve at two levels, said push-button valve including a

valve proper composed of two pistons and a connecting neck and having a flange at one end, serving as a stop in closed-valve position, and having means at the other end serving as a stop in opened-valve position, and means to deliver air under pressure from said air-receiving chamber to the under side of said push-button valve for closing the same.

6. In a rock drill, having a back head unit and a blow tube carried thereby, and having a working chamber, a main throttle valve carried in said head, said head having an air receiving chamber in communication with said throttle valve, means to deliver compressed air into said air receiving chamber, a duct between said air receiving chamber and the entrance of said blow tube, a push-button valve for controlling passage through said duct, said duct being independent of said throttle valve, another duct leading from said throttle valve to the entrant end of said blow tube independent of said push-button valve, a third duct leading from said throttle valve toward the working chamber of the drill, said throttle valve having ports for communication with said second and third ducts separately, said first duct having offset ports communicating with the valve chamber of said push-button valve at two levels, said push-button valve including a valve proper composed of two pistons and a connecting neck and having a flange at one end, serving as a stop in closed-valve position, and having means at the other end serving as a stop in opened-valve position, means to deliver air under pressure from said air-receiving chamber to the under side of said push-button valve for closing the same, and spring means for assisting the closing movement of said push-button valve.

EZRA B. MEAD.
